Primary Examiner — Cathron C Brooks*(74) Attorney, Agent, or Firm* — King & Spalding LLP(57) **CLAIM**

The ornamental design for a wall mounted luminaire, as shown and described.

DESCRIPTION

FIG. 1 is a top front perspective view of a wall mounted luminaire, showing our new design;

FIG. 2 is a bottom back perspective view thereof;

FIG. 3 is a top plan view thereof;

FIG. 4 is a bottom plan view thereof;

FIG. 5 is a front elevation view thereof;

FIG. 6 is a back elevation view thereof;

FIG. 7 is a left side elevation view thereof; and

FIG. 8 is a right side elevation view thereof.

FIG. 9 is another top front perspective view of the wall mounted luminaire, but shown with additional broken line subject matter;

FIG. 10 is a bottom back perspective view thereof;

FIG. 11 is a top plan view thereof;

FIG. 12 is a bottom plan view thereof;

FIG. 13 is a front elevation view thereof;

FIG. 14 is a back elevation view thereof;

FIG. 15 is a left side elevation view thereof; and,

FIG. 16 is a right side elevation view thereof.

The broken lines shown in the figures illustrate portions of the wall mounted luminaire that form no part of the claimed design.
